UNITED STATES PATENT OFFICE.

GEORGE E. DUNTON, OF NEW YORK, N. Y.

APPARATUS FOR TREATING MOLDS USED IN THE ART OF ELECTROTYPEING.

1,128,666.

Specification of Letters Patent. Patented Feb. 16, 1915.

Application filed June 23, 1914. Serial No. 846,826.

To all whom it may concern:

Be it known that I, GEORGE E. DUNTON, residing at New York city, in the county of New York and State of New York, a citizen of the United States, have invented a certain new and useful Improved Apparatus for Treating Molds Used in the Art of Electrotyping; and I do hereby declare the following to be a full, clear, and exact description of the invention, such as will enable others skilled in the art to which it pertains to make and use the same.

My invention relates to an improved apparatus for treating molds used in the art of electrotyping and more especially to an apparatus for insulating the mold from its molding pan or case.

In the art of electrotyping it is necessary to use a thin sheet of some metal as a back or base for the wax molds. These thin sheets of metal are commonly called molding pans or cases and are generally made from an alloy of lead, tin and antimony known as electrotype metal, although copper and even brass sheets are used, and are usually about one-eighth to three-sixteenths of an inch in thickness. These metal pans or cases are laid flat upon iron tables or slabs, hot wax is poured over them and allowed to cool, strips of iron having been placed around the edge to confine the wax. After the wax has been poured onto these pans or cases, on one side, they are known as filled pans or cases and are what the electrotypers uses to take the impression on or make his mold in. The wax surface is brushed over with black lead and the original form composed of types, illustrative cuts or whatever is desired to be electrotyped are pressed into this mold. To receive the desired deposit or cause the deposit on this wax it is necessary to make the surface of the wax conductive, meaning that the surface of the wax must be made metallic, so that when the mold is placed in the electrolytic bath it shall perform its function as the cathode in the electrical circuit of which it becomes a part. It is desirable, however, that only the surface of the wax shall be connected to or form a part of the electric circuit. To this end especially devised insulating hooks are provided for hanging the pan or case carrying the wax mold in the electrolytic bath and these hooks make no electrical connection between the metallic pan or case and the electrical circuit but they connect

the surface of the wax mold with the said circuit.

In blackleading the surface of a wax mold it is impossible to confine the coating of black lead to the surface of the wax mold alone as it will, no matter how careful you are, work over the edges of the wax mold onto the back of the pan or case, thus electrically connecting the surface of the wax mold with the metal pan or case.

My invention has for its object to provide an apparatus by which the electrically conductive portions of the wax mold outside the margins of the pressed surface of the mold and molding pan or case are rendered non-conductive.

It further has for its object to provide an apparatus by which the edges and margins of the mold and the edges and back of the molding pan or case are treated with an insulating coating by which they are rendered non-conductive.

It further has for its object to provide an apparatus for heating or melting an insulating substance and applying said insulating substance to the margins of a wax mold and to the back of its molding pan or case.

It further has for its object to provide an apparatus which is simple and inexpensive in construction, very durable, easy to operate and which will effect a great saving of time and labor and produce perfect results.

It further has for its object to provide an apparatus having a suitable receptacle containing an insulating substance in which the edges of a wax mold and its molding pan or case are adapted to be dipped, to a suitable depth, and the back of the molding pan or case also coated with said insulating substance, whereby the portions treated are rendered non-conductive and the deposit of metal is confined to the impressed or working portion of the wax mold and to any desired portion of its margin.

The invention consists in the several features and combination of features as more fully hereinafter described and claimed.

Referring to the drawings:—Figure 1 is a top plan view of my apparatus. Fig. 2 a front elevation, partly in section. Fig. 3 a central vertical cross section partly in elevation. Figs. 4, 5 and 6 are fragmentary detail views, partly in section, showing the different stages of the operation of apply-

ing the insulating or non-conductive coating. Fig. 7 a central longitudinal section of a mold and its molding pan after being treated by my apparatus.

5 In the drawings in which similar reference characters denote similar parts throughout the several views, 1 represents the melting pot of the apparatus, in which an insulating substance is adapted to be placed and melted, 2 the supporting legs, 3 a brace or tie for the legs, 4 the fluid insulating substance in said melting pot.

The insulating substance is melted by steam passing through a pair of heating cylinders 5 and 6, which are cast or otherwise formed in the melting pot and extend longitudinally thereof, connected and communicating with one another, at one end, by means of a U-shaped pipe 7. A steam supply pipe 8 is connected to the cylinder 5 and a steam exhaust or return pipe 9 is connected to the cylinder 6, steam from a boiler, or any other source, is adapted to be supplied to the cylinder 5 and caused to traverse and heat both of said cylinders 5 and 6, melt the insulating substance, and pass out by the pipe 9 and be returned to the boiler. The supply of steam to the cylinders 5 and 6 is regulated by means of a valve 10.

30 The driving shaft of the apparatus, indicated by 11, is mounted in suitable bearings 12, formed in the opposite ends of the melting pot, and a driving pulley 13 for the shaft 11 is loosely mounted on one end of said shaft and is adapted to be connected by means of a belt 14 to any suitable source of power. A slideable clutch 15 is provided on the shaft 11 for the purpose of throwing the shaft 11 into and out of operation as desired, said clutch being operated by means of a foot treadle or lever 16 operatively connected thereto by means of a bell-crank lever 17 and levers 18, 19 and 20 and a spiral spring 21 is provided for holding up the 45 foot treadle. A rotatable brush 22 is rigidly mounted on the driving shaft 11 and is designed to be partly immersed in the insulating substance in the melting pot and to cause said substance to be applied and cover evenly 50 the back of the molding pan.

On the opposite side of the melting pot from the driving shaft 11 a shaft 23 is mounted and on this shaft a roller 24, preferably covered with felt 25, is mounted and the shaft 23 is provided with a grooved pulley 27 which is operatively connected, by means of a crossed belt 28, with a grooved pulley 29 on the driving shaft 11. The cross belt is used to cause the roller 24 to turn or 60 rotate in the opposite direction from the brush 22.

At the rear of the melting pot a receiving rack 30 for the molds, after they have received their coating of insulating substance, 65 is provided having a rim 31 and rollers 32

and supported by means of suitable braces 31^a extending upward from the legs of the apparatus.

32 is a molding pan, made of metal or any other suitable material, which is provided with a hole 33 therethrough for the purpose of receiving the usual hook by which it is suspended in the electrolytic plating bath, 34 the wax mold in which an impression 35 has been made by forcing a form or cut into the same by pressure and 36 a hole in alignment with hole 33 of the molding pan. A metal connector strip 37 is embedded to the desired depth in the surface of the wax mold by heating it and applying it to the mold 80 while in a heated state.

38 is the insulating coating covering the edges and margins of the mold and molding pan after the mold has been dipped edgewise into the insulating substance contained in the melting pot and 39 the insulating coating which has been applied to the back of the molding pan by means of the brush 22.

The arrows 40 show the points where the insulating edge coating connects and merges 90 with the coating on the back of the molding pan.

The operation is as follows:—I place the required quantity of insulating substance in the melting pot and after melting it, to the desired degree, by causing steam to enter the cylinders 5 and 6 from the boiler, or other source of steam supply, through steam supply pipe 8 and after traversing and heating the cylinders the steam, or 100 water of condensation, returns through the pipe 9 to the boiler. I then take the mold and pan which have been prepared and blackleaded in the usual well known manner and dip them edgewise to the required depth in the insulating substance in the melting pot, see Fig. 4 of the drawings, which forms a coating on one side and then continue dipping, one side after another, until all sides have been treated to a coating. The brush 22 is then rotated by throwing in the clutch by means of the foot 110 treadle and causing the pulley 13, which in turn is operated by means of the belt 14, to rotate the shaft 11, and the felt covered roller being connected to the brush 22 by means of the crossed belt 28 is also caused to rotate. The molding pan, with the mold thereon with edges coated as before described, is then laid horizontally with the 120 back of the molding pan in contact with the rotatable brush, see Fig. 5 of the drawings, and as it is pushed forward, with the brush rotating in the opposite direction, said brush applies and distributes the insulating substance over the back of the molding pan and forms an even homogeneous coating thereon, and the felt covered roller, being rotated in the opposite direction from the brush, not only serves as 125

130

a guide to the molding pan but applies and smooths insulating substance on the back thereof and on the completion of the coating the pan and its mold will abut against the rim of the receiving rack and rest on said rack and its rollers.

Usually it will suffice to pass the molding pan over the rotatable brush and felt covered roller once to obtain the necessary coating but it can be passed over said brush and roller as many times as is desired to acquire the requisite coating.

The method is claimed in my application for patent filed June 23d, 1914 Serial Number 846825.

I do not desire to be understood as limiting myself to the specific details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right to all such variations and modifications as properly fall within the scope of my invention and the terms of the following claims.

What I claim is:—

1. In an apparatus for treating molds used in the art of electrotyping, means for applying an insulating substance to the molding pan and also means for applying additional insulating substance to the molding pan and smoothing the same, said means having an unobstructed space thereabove.

2. In an apparatus for treating molds used in the art of electrotyping, a receptacle adapted to contain an insulating sub-

stance, rotatable means for applying the insulating substance to a molding pan, rotatable means for applying additional insulating substance to a molding pan and smoothing the same, the first mentioned rotatable means being spaced apart from the last mentioned rotatable means for the purpose of affording space to allow the edges of the mold and molding pan to be inserted into said receptacle and treated with insulating substance.

3. In an apparatus for treating molds used in the art of electrotyping, a receptacle adapted to contain an insulating substance, a rotatable brush and a rotatable roller rotatable in opposite directions and spaced apart for the purpose of affording space to allow the edges of the mold and molding pan to be inserted into said receptacle and treated with insulating substance.

4. In an apparatus for treating molds used in the art of electrotyping, a receptacle adapted to contain an insulating substance, consisting of rotatable means for applying the insulating substance to a molding pan and rotatable means for applying additional insulating substance to a molding pan and smoothing the same, said rotatable means having a free space between them for the purpose of allowing a mold and molding pan to be inserted into the receptacle and treated with the insulating substance.

In testimony whereof I affix my signature in the presence of two witnesses.

GEORGE E. DUNTON.
